(57) CLAIM

The ornamental design for a beverage cup, as shown and described.

DESCRIPTION

FIG. 1 is a front view of a beverage cup showing my new design;

FIG. 2 is a rear view thereof;

FIG. 3 is a left side view thereof, a right side view being a mirror image;

FIG. 4 is a top view thereof;

FIG. 5 is a bottom view thereof; and,

FIG. 6 is a top and front side perspective view thereof. The broken lines in the drawing views represent unclaimed portions of a beverage cup, which are included for the purpose of illustrating unclaimed environment only and form no part of the claimed design.

1 Claim, 5 Drawing Sheets
